UNITED STATES PATENT OFFICE.

ROBERT T. TAYLOR, OF GASTONVILLE, PENNSYLVANIA, ASSIGNOR OF ONE-HALF TO
JOE NEELIS, OF GASTONVILLE, PENNSYLVANIA.

BOTTLE CLOSURE AND SEAL.

962,396.

Specification of Letters Patent. Patented June 21, 1910.

Application filed October 7, 1909. Serial No. 521,558.

To all whom it may concern:

Be it known that I, ROBERT T. TAYLOR, a citizen of the United States of America, residing at Gastonville, in the county of Washington and State of Pennsylvania, have 5 invented certain new and useful Improvements in Bottle Closures and Seals, of which the following is a specification, reference being had therein to the accompanying drawing.

10 This invention relates to bottle closures and seals, and the objects of my invention are to provide a bottle with a closure that can be easily removed and again replaced 15 to seal the bottle, and to furnish a bottle with a closure that will be simple in construction, durable and highly efficient for the purposes for which it is intended.

20 Other objects of the invention are to provide detachable means for positively sealing a bottle, and to provide a closure that can be advantageously used in connection with beer bottles.

25 These and such other objects as may hereinafter appear are attained by a mechanical construction that will be hereinafter described in detail and then claimed, and reference will now be had to the drawing forming a part of this specification, wherein 30 there is illustrated a preferred embodiment of the invention; but it is to be understood that the structural elements thereof can be varied or changed without departing from the spirit and scope of the invention.

35 In the drawing:—Figure 1 is an elevation of a bottle provided with my improved closure, Fig. 2 is a similar view partly broken away and partly in section, Fig. 3 is a plan of a detached closure, Fig. 4 is a 40 front elevation of the same, and, Fig. 5 is an enlarged longitudinal sectional view of a detached closure.

In the accompanying drawing, 1 denotes 45 a metallic disk having the edge thereof cut away, as at 2, while the remaining edge is bent downwardly and crimped, as at 3 to form a cap adapted to slide upon the rim 4 of a bottle neck 5.

Secured to the top of the disk 1 by rivets 50 6 or other fastening means is a resilient strip of metal 7 having one end thereof projecting over the cut away edge of the disk 1, the projecting edge being bent downwardly upon a curvature corresponding to the rim 4 55 of the bottle neck 5, whereby the projecting

end will engage under the rim and retain the closure upon the bottle neck.

The inner side of the disk 1 can be provided with a circular piece of cork 8, similar to an ordinary bottle cap, for sealing the 60 bottle neck.

My improved closure can be easily swung over the upper end of a bottle neck, or the curved end of the resilient strip of metal can be elevated sufficiently to permit of the 65 closure being slidably mounted upon the bottle neck until correctly positioned, when by releasing the resilient strip of metal the curved end thereof will engage the rim 4 and retain the bottle in a closed and sealed condition. 70

The closure can be pressed from sheet metal and the resilient strip of metal, which serves functionally as a catch, easily secured 75 to the top of the closure.

Having now described my invention what I claim as new, is:—

1. A bottle closure comprising a cap formed from a flat disk having the marginal portion at one side thereof cut-away to provide a rounded edge and the remaining part of the marginal portion bent downwardly with respect to the said rounded edge, said downwardly bent marginal portion curvilinear in vertical section and adapted to 80 overlap the bead of a bottle neck, and a resilient strip mounted upon and centrally of the upper face of the disk and extending from the upper terminus of said bent marginal portion to beyond said rounded edge, 85 that portion of said strip projecting from said rounded edge curved and depending at right angles with respect to said rounded edge, and detachably engaging the bead of the bottle for securing the cap in position, 90 and means at one side of the center of the cap opposite to the curved downwardly projecting portion of the strip for fixedly securing one end of the strip upon the upper 95 face of the disk. 100

2. A bottle closure comprising a cap formed from a flat disk having the marginal portion at one side thereof cut-away to provide a rounded edge and the remaining part of the marginal portion bent downwardly with respect to the said rounded edge, said 105 downwardly bent marginal portion curvilinear in vertical section and adapted to overlap the bead of a bottle neck, and a resilient strip mounted upon and centrally of 110

the upper face of the disk and extending from the upper terminus of said bent marginal portion to beyond said rounded edge, that portion of said strip projecting from 5 said rounded edge curved and depending at right angles with respect to said rounded edge, and detachably engaging the bead of the bottle for securing the cap in position, and a plurality of hold-fast devices at one 10 side of the center of the cap opposite to the

curved downwardly projecting portion of the strip for fixedly securing one end of the strip upon the upper face of the disk.

In testimony whereof I affix my signature in the presence of two witnesses.

ROBERT T. TAYLOR.
